(57) **CLAIM**

The ornamental design for a phone case attachment, as shown and described.

DESCRIPTION

FIG. 1 is a perspective view of a phone case attachment showing my new design;

FIG. 2 is a front view thereof;

FIG. 3 is a back view thereof;

FIG. 4 is a side view thereof;

FIG. 5 is top view thereof;

FIG. 6 is another perspective view thereof displaying an environment with an unclaimed phone case;

FIG. 7 is a front view thereof;

FIG. 8 is a back view thereof;

FIG. 9 is a side view thereof;

FIG. 10 is a top view thereof;

FIG. 11 is another perspective view thereof, showing additional environment;

FIG. 12 is another perspective view thereof displaying another environment with an unclaimed phone case;

FIG. 13 is a front view thereof;

FIG. 14 is a rear view thereof;

FIG. 15 is a side view thereof;

FIG. 16 is a top view thereof; and,

FIG. 17 is another perspective view thereof, showing additional environment.

The broken lines illustrating portions of the phone case attachment do not form a part of the claimed design. The broken lines depicting a phone case, a phone, and a hand in FIGS. 6–17 are included for purposes of illustrating environment and demonstrating usage, and form no part of the claimed design. The unshaded surfaces bound by, or underlying, broken lines form no part of the claimed design.
